Primary Examiner—Jeffrey D. Asch*Assistant Examiner*—Bridget L Eland(74) *Attorney, Agent, or Firm*—Banner & Witcoff, Ltd.(57) **CLAIM**

The ornamental design for set of key buttons for a handset, as shown and described.

DESCRIPTION

FIG. 1 is a front view of a set of key buttons for a handset showing our new design; and,

FIG. 2 is a perspective front view thereof.

The broken line showing of the remainder of the handset is for illustrative purposes only and forms no portion of the claimed design.
